UNITED STATES PATENT OFFICE

WALTER D. BUTZ, OF NORRISTOWN, PENNSYLVANIA, ASSIGNOR OF ONE-HALF TO LOUIS
N. D. WILLIAMS, OF ELKINS PARK, PENNSYLVANIA

SELECTIVE NEEDLE CONTROL MECHANISM FOR KNITTING MACHINES

Application filed April 9, 1930. Serial No. 442,769.

This invention relates to mechanism useful in connection with knitting machines to produce ornamental and other effects in the fabrics knit on them. In certain forms of embodiment such as hereinafter fully disclosed, the mechanism of my invention is especially suited for incorporation in seamless hosiery knitting machines, to form, incident to fashioning of the toe pockets of the 10 stockings, lines of tuck stitches parallel to the characteristic diagonal sutures of such hosiery, to the end that the stockings are rendered more attractive and that unsightly puckering around the outer ends of the 15 diagonal sutures aforesaid is precluded. This application may therefore be considered as related in a general way to my two co-pending patent applications, Serial Nos. 336,686 and 364,370 filed respectively on February 1, 1929 20 and May 20, 1929. In these prior applications, the selection of predetermined needles for tucking to produce the above indicated effects, was controlled entirely by the end needles of the active group during reciprocating knitting.

My present invention has for its main objects to enable selection of predetermined needles for tucking from amongst the active group under control of the end needles of the 30 inactive group during the corresponding phases of the knitting; and to provide a simple automatic mechanism with needle selecting instrumentalities that derive motion from the element provided in the machines 35 (the drop picker in the case of circular machines) for moving the needles from the inactive to the active levels.

A further object is to afford facilities whereby the activity of the selective needle 40 control mechanism is governed by the means provided in standard knitting machines for timing the various phases of stocking knitting.

Still other objects and attendant advantages will be manifest from the detailed description hereinafter of the typical embodiment shown in the attached drawings, where- 45 in Fig. I is a fragmentary view of a stocking having in parallelism with the usual diagonal fashioning sutures at opposite sides

of its toe, lines of tuck stitches such as may be produced with the aid of my improved selective needle control mechanism.

Fig. II is a diagrammatic view illustrating the fashioning of the stocking toe with the supplemental tuck lines.

Fig. III is a part plan view of a typical circular knitting machine embodying the selective needle control mechanism of my invention, the needle cylinder having been removed to expose the knitting cams.

Figs. IV and V are detail sections taken as indicated, respectively, by the arrows IV—IV and V—V in Fig. III.

Fig. VI is a fragmentary plan sectional view taken as indicated by the arrows VI—VI in Figs. IV and V.

Fig. VII is a detail section taken as indicated by the arrows VII—VII in Figs. IV and VI.

Fig. VIII is a detail view taken as indicated by the arrows VIII—VIII in Fig. IV.

Fig. IX is a linear development of the cam ring of the machine and showing certain supplemental cams embodied in my needle control mechanism.

Figs. X—XVI are views like Fig. IX illustrating successive steps in the operation of the control mechanism.

Referring in detail to these illustrations, the numeral 20 designates the cam ring of the knitting machine, said cam ring being stationarily supported in a bed plate 21 and provided with the customary needle actuating cams including stitch cams 22, 23, top and bottom center cams 24, 25. The cam ring 20 is further equipped with a vertically swingable cam 26 for raising the long butt needles, indicated by heavy shaded lines at N in Fig. IX, to inactive level preparatory to the fashioning phases of the knitting; and for restoring said needles to the active level at the completion of the fashioning operations. As is usual in circular stocking knitting machines, the long butt needles N are equal in number to a complementary series of short butt or fashioning needles indicated by light lines at N' in Figs. IX—XVI. The needles N, N' are all afforded guidance for 100

up and down movement individually in the grooves of the cylinder 27 which is shown in Figs. IV and V as being secured to a bevel gear 28 that occupies a recess in the bed plate 21. By suitable mechanism (not illustrated) coordinated with the bevel gear 28, the needle cylinder 27 is rotated or oscillated as required in the knitting of seamless stockings after a well known manner. The lifting pickers 43, 44 by which the short butt needles N' are successively raised from the normal or active level to the idle or tucking level during narrowing of the heel and toe pockets of the stockings, are indicated at 29, 30; while the depressing picker whereby said short butt needles are restored to activity during the widening phases of heel and toe pocket knitting, is indicated at 31.

Proceeding now to my selective needle control mechanism, the same comprises, as shown in Figs. III-VII, a bracket 32 which is adapted to be substituted in place of the usual bracket for the depressing picker 31, and which is provided with apertures spaced to correspond with the original tapped holes in the circumferential flange 33 of the cam ring 20 for the securing screws 34. The depressing picker 31 is in the present instance pivoted for vertical swinging movement about a horizontal axis 35 in an arbor 36 which is swingable, in turn, about a vertical axis in the bracket 32. The depressing picker 31 is thereby accorded capacity for universal movement to follow, under the yielding action of a spring 37, the downward angular paths determined for it by a wing cam 38 as said picker is swung to the right or left in the performance of the picking action. The wing cam 38 has the usual double lobed contour as shown in Figs. IX-XVI, and is secured to the top of the bracket 32. From Fig. IV it will be noted that the arbor 36 has point-bearing 39, at its lower end, with the base portion of the bracket 32, while its upper end is engaged by a point-screw 40 which is adjustable in the top of said bracket. Normally, during round and round knitting and also during the narrowing phases of the heel and toe pocket knitting, the depressing picker 31 is held lowered in idle position through engagement of its tail 31a by a horizontal projection 41 at the top of a rod 42 which is vertically slidable in the bed plate 21 and adapted to be operated from the pattern drum (not shown) of the machine. With the depressing picker 31 I associate a pair of special lifting pickers 43, 44, which, like said depressing picker, are accorded capacity for universal movement by virtue of being pivoted on horizontal axes 45, 46 respectively in arbors 47, 48 vertically mounted in the bracket 32 and symmetrically disposed at opposite sides of the arbor 36, as shown in Figs. III and VI. Individual compression springs 49 tend to urge the special lifting pickers 43, 44 downward against

stop projections 50, 51 (Fig. VII) formed on oppositely sloping incline cams 52, 53 whereby said pickers are guided as herein-after more fully explained. The cams 52, 53 are fixedly secured to lugs 54, 55 upstanding from the base portion of the bracket 32. By means of a pull spring 56 (Fig. VI) in tension between them, the special lifting pickers 43, 44 are moreover yieldingly maintained respectively in contact with the opposite vertical edges 57, 58 of a slide piece 59 which engages an arcuate groove 60 in the base portion of the bracket 32 for movement concentrically with respect to the axis of the needle cylinder 27. In order to predetermine alternate actuation of the special lifting pickers 43, 44 under the influence of the depressing picker 31, the arbor 36 of said depressing picker is fitted with a coupling finger 61 which normally engages a central notch 62 in the slide piece 59. The finger 61 is pivoted to the arbor 36 so as to be swingable upwardly against the action of a spring 63 (Fig. IV) clear of the notch 62 in the slide piece 59, by means of a horizontal projection 64 at the top of a vertical rod 65. Like the rod 42, this rod 65 is slidable in the bed plate 21 of the machine. A spring 66 tends to maintain the lower rounded end of the rod 65 in cooperative engagement with a toothed cam wheel 67 which is adapted to be progressively rotated through picking of an attached ratchet wheel 68 by a pawl 69, see Figs. IV and VIII. This pawl 69 may be coordinated with the pattern mechanism (not shown) of the machine for intermittent operation to control the activity of the special pickers 43, 44 in the manner presently set forth. The ends of the special pickers 43, 44 are, in the present instance, reduced to the width of a single needle butt, and, as shown in Figs. V and IX, normally occupy positions in a common horizontal plane. As the active (short butt) needles N' approach the region of the depressing picker 31 from opposite sides incident to oscillatory knitting, they are elevated slightly above the normal rest ledge 70 of the cam ring 20 by a stationary cam piece 71 which is secured to the bracket 32. From Figs. IX-XV it will be observed that the cam piece 71 is recessed downwardly at the center with provision of a clearance interval 72 for the ends of the special pickers 43, 44 beneath the travel of the active short butt needles N'. After passing beyond the region of the depressing picker 31 in either direction, the active needles N' are brought down to the normal rest level 70 by means of lowering guard cams 73, 74 likewise secured to the picker bracket 32 adjacent the ends of the cam piece 71.

The operation of my invention is as follows: Let it be assumed that the stocking of Fig. I has been knit down through the leg, the heel and foot, as well as down through the narrowed half of the toe T in Fig. II to

the line $a-a$; and that the widening phase of the toe fashioning is about to commence with the short butt needles N' at the tucking level except for the few left at the active level, see Fig. IX. As the needle cylinder 27 moves to the right in initiating the widening phase of the knitting, the depressing picker 31 slips up into the gap in the rank of idle needles and is ultimately engaged by the leading needle 75 of said rank, as illustrated in Fig. X. Upon further movement of the machine in the direction of the arrow in the illustration last referred to, the depressing picker 31 is obliged to descend at an angle under the guidance of the wing cam 38 and carries down with it the needle 75 and the immediate neighboring needle after a manner common to widening operations on circular machines. Concurrently with such descent of the depressing picker 31 the special picker 43 in advance, in the direction of rotation of the machine, engages a needle 76 from amongst the active group and under the movement induced through the medium of the slide piece 59 by the depressing picker 31, said special picker 43 is caused to follow the counter-inclined upward path defined for it by the cam 52, thereby carrying the selected needle 76 up to a level above the guard cam 73, as shown in Fig. XI, in readiness to be finally lifted to the tucking level by the center cam 24. All the active needles are thereupon caused to pass through the knitting cams in the usual manner to knit a course of the fabric while the selected needle 76 is maintained temporarily at the inactive or tucking level. At the completion of this first oscillation of the machine, the parts occupy the position shown in Fig. XII. During the succeeding movement of the machine in the reverse direction, the depressing picker 31 is engaged by the leading needle 77 at the opposite side of the gap in the idle rank as shown in Fig. XIII, and carries such leading needle, together with its immediate neighbor, down to the active level; while the special picker 44 (now in advance of said depressing picker) selects another needle 78 from amongst the active group and lifts it concurrently as shown in Fig. XIV. Directly upon release after having performed the function just described of it, the depressing picker 31 rises in time to engage the needle 76, Fig. XV, previously elevated to the tucking level, and restores said needle to the active level as shown in Fig. XVI in readiness to pass through the knitting cams with the others in the active group during the succeeding oscillation of the machine or movement of the needles to the right. In order to prevent raising of another needle from the active group by the special picker 44 as the needle 76 is restored in the manner just explained, said picker 44 is temporarily released from the influence of the depressing picker 31

through lifting of the coupling finger 61 (Figs. IV and VII) from the notch 62 in the slide piece 59 under control of the cam wheel 67. Thus during each oscillation of the machine, an individual needle is lifted from amongst those of the active group N' first at a definite distance from the leading needle of the inactive group N at one side, and then at a corresponding distance from the leading needle of the inactive group N at the other side for maintenance at the tucking level only while the current course of the fabric is being knit. Due to the gradual enlargement of the breach in the inactive rank of needles and attendant changing of the end needles as the widening operation proceeds, repetition of the above cycle will obviously be attended by lifting of successively neighboring needles from amongst the active group N' with resultant formation of lines of tuck stitches L, L (Figs. I and II) parallel to the usual diagonal sutures S in the toes T of stockings produced by the machine. Ordinarily, while the heel pocket of the stocking is being knit, the cam wheel 67 is maintained quiescent with the rod 65 occupying one of the peripheral notches between the teeth of said wheel, so that the finger 61 is held out of the notch 62 in the slide 59 by the spring 63 (Fig. IV) to prevent actuation of the special pickers 43, 44 by the depressing picker 31.

If desired, the cam wheel 67 may be set in motion during widening of the heel pocket to determine formation of tuck lines precisely as above explained in connection with knitting of the toe pocket T . Moreover, by suitably controlling the picking of the cam wheel 67, the frequency of the tuck stitches along the lines L, L in the stocking of Fig. I may be extensively varied.

While the ends of the special pickers 43, 44 are reduced to the width of a single needle butt, it is obvious they can be wider so that more than one needle may be selected and lifted by them at each actuation, with formation of correspondingly wider tuck lines.

While I have described my improved selective needle control mechanism in connection with a circular stocking knitting machine, it is not to be regarded as limited to such use: nor is its operation to be considered as restricted to reciprocatory knitting alone, since by various modifications within the skill of an experienced knitting machine mechanic, its utility may be extended to determine the formation of tuck effects other than the one herein exemplified.

Having thus described my invention, I claim:

1. The combination in a knitting machine embodying a multiplicity of independent needles, and means for subdividing the needles into active and inactive groups at different levels; of selective needle control mechanism including means governed by the end needles

of the inactive group to select individual needles at a distance from the end needles of the active group during knitting of each course of the fabric, and to move such selected needles to the inactive level.

2. The combination in a knitting machine embodying a multiplicity of independent needles, and means for subdividing the needles into active and inactive groups at different levels; of selective needle control mechanism including means governed by the end needles of the inactive group to select individual needles at a distance from the end needles of the active group during knitting of each course of the fabric, and to move such selected needles to the inactive level.

4. The combination in a knitting machine embodying a multiplicity of independent needles, means for subdividing the needles into active and inactive groups at different levels, and an element for moving individual needles from the inactive to the active levels incident to knitting of successive fabric courses; of selective needle control mechanism including instrumentalities operating concurrently with the element aforesaid to select individual needles at a distance from the end needles of the group at the active level and to move such selected needles to the inactive level.

50 55 60 65 70 75 80 85 90 95 100 105 110 115 120 125 130

5. The combination in a knitting machine embodying a multiplicity of independent needles, means for subdividing the needles into active and inactive groups at different levels, and an element for moving individual needles from the inactive to the active levels incident to knitting of successive fabric courses; of selective needle control mechanism including instrumentalities deriving movement from the element aforesaid to concurrently select individual needles at a distance from the end needles of the group at the active level and to move such selected needles to the inactive level.

60 65 70 75 80 85 90 95 100 105 110 115 120 125 130

6. The combination in a knitting machine embodying a multiplicity of independent needles, means for subdividing the needles into active and inactive groups at different

levels, and an element for moving end needles of the inactive group to the active level incident to knitting of successive fabric courses; of selective needle control mechanism including instrumentalities governed by the end needle of the inactive group to select individual needles from the active group at a definite distance from said end needle and to move such selected needles to the inactive level.

7. The combination in a knitting machine embodying a multiplicity of independent needles, means for subdividing the needles into active and inactive groups at different levels, and an element for moving individual needles from the inactive to the active levels incident to knitting of successive fabric courses; of selective needle control mechanism including instrumentalities governed by the end needles of the inactive group to select, during knitting of each fabric course, individual needles at a distance from the end needles of the active group and to move such selected needles temporarily to the inactive level to be restored to the active level by the element aforesaid during knitting of the succeeding fabric course.

8. The combination in a circular knitting machine embodying a series of fashioning needles; of a selective needle control mechanism governed by the changing end needles of the inactive group incident to fashioning by oscillatory knitting to automatically select individual needles at a distance from the end needles of the active group during each oscillation of the machine, and to lift such selected needles to the tucking level.

9. The combination in a circular knitting machine embodying a series of fashioning needles; of a selective needle control mechanism governed by the changing end needles of the inactive group incident to fashioning by oscillatory knitting to automatically select individual needles from the active group at a definite distance from said changing end needles during each oscillation of the machine, and to lift such selected needles to the tucking level.

10. The combination in a circular knitting machine embodying a series of fashioning needles, and fashioning instrumentalities including a drop picker for depressing the fashioning needles successively from the inactive level to the active level incident to fashioning by oscillatory knitting; of a selective needle control mechanism comprising means operative concurrently with the lowering of an end needle of the inactive group during each oscillation of the machine by the depressing picker, to raise at a distance from the end needles of the active group, a predetermined needle, and to elevate such selected needle to the inactive level to remain so raised until restored to the active level by

the drop picker during the immediately succeeding oscillation.

11. The combination in a circular knitting machine embodying a series of fashioning needles, and fashioning instrumentalities including a drop picker for depressing the fashioning needles successively from the inactive or tucking level to the active level incident to fashioning by oscillatory knitting; of a selective needle control mechanism comprising means operatively coordinated with and adapted for actuation by the depressing picker aforesaid to select individual needles at a distance from the end needles of the active group during each oscillation of the machine, and to lift such selected needles to the tucking level.

12. The combination in a circular knitting machine embodying a series of fashioning needles, and fashioning instrumentalities including a drop picker for depressing the fashioning needles successively from the inactive or tucking level to the active level incident to fashioning by oscillatory knitting; of a selective needle control mechanism comprising special pickers operatively coordinated with and adapted for actuation by the depressing picker aforesaid to select individual needles at a distance from the end needles of the active group during each oscillation of the machine, and to lift such selected needles to the tucking level.

13. The combination in a circular knitting machine embodying a series of fashioning needles, and fashioning instrumentalities including a drop picker for depressing the fashioning needles successively from the inactive or tucking level to the active level incident to fashioning by oscillatory knitting; of a selective needle control mechanism comprising means operatively coordinated with and adapted for actuation by the depressing picker aforesaid to select individual needles at a distance from the end needles of the active group during each oscillation of the machine, means to lift such selected needles to the tucking level, and means operative to temporarily release the needle selecting means aforesaid from the influence of the depressing picker at the initiation of each oscillation to permit said depressing picker to restore previously selected and elevated needles to the active level.

14. The combination in a circular knitting machine embodying a series of fashioning needles and fashioning instrumentalities including a picker for depressing the fashioning needles successively from the inactive or tucking level to the active level incident to fashioning by oscillatory knitting; of a selective needle control means comprising special pickers coordinated with and adapted for actuation by the depressing picker aforesaid to select individual needles at a distance from the end needles of the active group during

each oscillation of the machine, means to lift such selected needles to the tucking level, and means operative to temporarily release the special pickers from the influence of the depressing picker at the initiation of each oscillation to permit said depressing picker to restore previously selected and elevated needles to the active level.

15. The combination in a circular knitting machine embodying a series of fashioning needles, and fashioning instrumentalities including a picker for depressing the fashioning needles successively from the inactive or tucking level to the active level incident to fashioning by oscillatory knitting; of a selective needle control mechanism including special pickers mounted for independent movement to opposite sides of the depressing picker aforesaid, and coordinating means whereby the special picker in advance of the depressing picker is actuated during each oscillation of the machine through movement derived from said depressing picker to select a needle at a distance from the end needles of the active group and to lift such selected needle to the tucking level.

16. The combination in a circular machine embodying a series of fashioning needles, and fashioning instrumentalities including a picker for depressing the fashioning needles successively from the inactive or tucking level to the active level incident to fashioning by oscillatory knitting; of a selective needle control mechanism comprising special pickers mounted for independent movement at opposite sides of the depressing picker, a slide interposed between the special pickers, spring means for maintaining the special pickers yieldingly in contact with the opposite ends of the slide, stops to limit the movement of the special pickers toward each other under the influence of the spring means, and means to connect the slide aforesaid with the depressing picker whereby the special picker in advance of the depressing picker during each oscillation of the machine is caused to select a needle at a distance from the end needles of the active group and to lift such selected needle to the tucking level.

17. The combination in a circular machine embodying a series of fashioning needles, and fashioning instrumentalities including a picker for depressing the fashioning needles successively from the inactive or tucking level to the active level incident to fashioning by oscillatory web knitting; of a selective needle control mechanism comprising special pickers mounted for independent movement at opposite sides of the depressing picker, a slide interposed between the special pickers, spring means to maintain the special pickers yieldingly in contact with the opposite ends of the slide, stops to limit the movement of the special pickers toward each other under the influence of the spring

means, means coupling the slide with the depressing picker whereby the special picker in advance of the depressing picker during each oscillation of the machine is caused to 5 select a needle at a distance from the end needles of the active group and to lift such selected needle to the tucking level, and means for temporarily uncoupling the slide for release of the special pickers to permit said depressing picker to restore the selected needle to the active level during the immediately 10 succeeding oscillation of the machine.

18. The combination in a circular knitting machine embodying a series of fashioning needles, and fashioning instrumentalities including a picker for depressing the fashioning needles successively from the inactive or tucking level to the active level incident to fashioning by oscillatory knitting; of a 15 selective needle control mechanism including special pickers mounted for independent movement at opposite sides of the depressing picker, a slide interposed between said special pickers, spring means to maintain the special pickers yieldingly in contact with opposite ends of the slide, stops for limiting movement of the special pickers toward each other under the influence of the spring means, a coupling finger coordinated with the depressing 20 picker and engaging a notch in the slide aforesaid whereby the special picker in advance of the depressing picker during each oscillation of the machine is caused to select a needle at a distance from the end needles 25 of the active group and to lift such selected needle to the tucking level, and means for automatically disconnecting the coupling finger from the slide to release the special picker actuated as aforesaid from the influence of 30 the depressing picker during the immediately succeeding oscillation of the machine to permit restoration of the selected needle to the active level by said depressing picker.

19. The combination in a circular knitting machine embodying a series of fashioning needles, and fashioning instrumentalities including a picker for depressing the fashioning needles successively from the inactive or tucking level to the active level incident to 35 fashioning by oscillatory knitting; of a selective needle control mechanism including special pickers mounted for independent movement at opposite sides of the depressing picker, a slide interposed between said special pickers, spring means to maintain the special pickers yieldingly in contact with opposite ends of the slide, stops for limiting movement of the special pickers toward each other under the influence of the spring means, a coupling 40 finger coordinated with the depressing picker and engaging a notch in the slide aforesaid whereby the special picker in advance of the depressing picker during each oscillation of the machine is caused to select 45 a needle at a distance from the end needles

of the active group and to lift such selected needle to the tucking level, a slide rod with a projection for engaging a tail of the coupling finger to disconnect the slide with release of the special picker actuated as aforesaid from the influence of the depressing picker during the immediately succeeding oscillation of the machine, thereby to permit said depressing picker to restore the previously selected needle to the active level, and an 50 intermittently rotating cam wheel to actuate the slide rod for the purpose indicated.

20. The combination in a hosiery knitting machine embodying a series of fashioning needles; of a selective needle control mechanism governed by the changing end needles of the inactive group incident to reciprocatory toe-pocket knitting for automatically selecting a needle from the active group at a definite 55 distance from the changing end needle of the inactive group during each reciprocation of the machine as well as lifting such selected needle to the tucking level, and, during the immediately succeeding reciprocation to restore such selected needle to the active level, with formation by repetitions of the indicated cycle, of lines of tuck stitches in parallelism with the diagonal sutures at opposite sides of the toe pocket.

In testimony whereof, I have hereunto 95 signed my name at Philadelphia, Pennsylvania, this 3rd day of April, 1930.

WALTER D. BUTZ.
